LEVER

Harry M. Roeser, Chicago, Ill., assignor to
Streeter-Amet Company, Chicago, Ill., a corporation of Illinois

Application April 8, 1944, Serial No. 530,217

3 Claims. (Cl. 308—2)

This invention relates to levers and the like employing knife edge and similar pivots, and among other objects aims to provide a simple and improved knife pivot construction for adjusting the lever ratio and for other purposes. The nature of the invention may be readily understood by reference to one construction embodying the invention and shown in the accompanying drawing.

In said drawing,

Fig. 1 is an elevation of a typical scale lever system.

Fig. 2 is an enlarged elevation (nearly full scale) of an adjustable lever pivot; and

Fig. 3 is a transverse plan section taken on the plane 3—3 of Fig. 2.

In levers for scales and other systems for transmitting force or movement, it is common to employ so-called knife edges or similar structures to form the pivots and fulcrums. Generally the knife edges are provided by hard steel sections (often of so-called pear-shaped section) having their extremities sharpened to a knife edge and inserted through an opening in the lever, the sharpened knife edge portions projecting from the opposite sides of the lever. When a knife edge becomes dull, it may be sharpened either by re-stoning the old knife edge or replacing it with another sharp knife edge. In either case, it is very difficult to provide sharp knife edges without changing the lever ratio or otherwise disturbing the relation between the knife edges of the lever. These difficulties are caused, among other reasons, by the circumstance that in forming or sharpening a knife edge, it is practically impossible to control the location of the sharpened edges with reference to the axis or some other fixed part of the knife edge section. The knife edge is usually sharpened by grinding or stoning the bevel faces of the hard steel insert until a sharp edge results. Removal of too much metal from one face of the bevel displaces the knife edge from its proper position. A displacement as little as .002 of an inch would be multiplied ten times in a lever having a ten to one ratio. Yet it is practically impossible by any simple measuring means to determine whether or not the sharpened edge is within .010" of its original or correct position.

Efforts have been made heretofore to provide adjustment by making the knife edge rotatable in the beam, but the knife edges were not held in adjusted position sufficiently firmly. Either the rotatable member in which the knife edge was seated for rotary adjustment was not firmly

locked in adjusted position or the knife edge was not firmly locked in the rotatable member. Knife edges are subjected to great stresses and adjustability is not practical unless the knife edge can be held in adjusted position practically as firmly as though the parts were integral.

In the present improvement both the knife edge and its rotary bearing are firmly locked in adjusted position. In the illustrative construction, the knife edge is represented by an insert 10 of hard steel or the like, sharpened to provide a knife edge 11. The sides of the knife edge section are advantageously rectangular so as to make it possible to provide an insert of uniform dimensions. Standard tool steel stock may be used. This may be finished to uniform thickness with the knife edge parallel to sides and base of the section. Intermediate its ends, the knife edge is provided with the bearing 12 of circular section comprising a separate locking member 13 having therein an opening 14 of a shape and size to receive the knife edge insert 10. The locking member 13 is mounted in an opening 15 in the beam or lever 9 of substantially the diameter of the locking member 13 so that the latter may fit closely in the opening. The locking member may advantageously compose a section of cold rolled steel stock which is characterized by uniformity in dimension. The opening 15 is advantageously formed by drilling so as to be of exact size and exactly square with the beam. Opening 14 in the locking member is machined therein with its sides parallel to the axis 14 of the cylindrical periphery of the locking member 13, so that upon rotation the knife edge 12 moves parallel to itself.

The opening 15 in the lever is located as closely as may be in ordinary shop practice to provide the proper lever ratios. Correction of the lever ratios is effected after the locking members and 40 knife edges have been inserted in the several openings of the lever, by rotating the knife edge and its locking member in one direction or other to shift the knife edge 11 in relation to the fulcrum or other pivot points of the lever and thereby to establish the correct lever ratios. This may conveniently be done simply by placing a wrench over a projecting portion of the knife edge and twisting it in the desired direction. Thereafter the knife edge and its locking member are firmly secured in adjusted position.

In the improved construction both the knife edge and its bearing or locking member are firmly locked in adjusted position by expanding the periphery of the locking member so as to fasten it tightly in the lever and simultane-

ously contracting the sides of opening 14 in the locking member without impairing the surface contact with the knife edge. In other words the bearing members are not expanded at the expense of the contact with the knife edge. This is effected in the present instance by providing the locking member with independent resilient elements which are deflectable both inwardly and outwardly. As here shown, these deflectable portions constitute small portions of the locking member made deflectable by slotting the locking member as at 16. The slots in this instance extend from the periphery a substantial distance through the locking member and terminate at 17, a short distance from the periphery 10 of the locking member. Thus, the outer portions 18 are resilient to deflect outwardly for locking the locking member in the lever and the inner portions 19 are deflectable inwardly to lock the knife edge tightly in the locking member. Neither effects its locking action at the expense of the other. The extremity of the slot 17 terminates in a large opening to prevent development of cracks in the locking member. Similarly the corners 20 of the opening 14 are similarly provided with rounded surfaces to prevent the development of cracks. The outer and inner portions 18 and 19 are in this instance deflected by taper pins 21 which are driven tightly into enlarged holes 22 in the slots 16 when the knife edge has been properly adjusted. Thus the knife edge is locked in the bearing simultaneously with the locking of the latter in the lever, and in each case full surface contact between each of the parts is maintained. The knife edge may be released for adjustment simply by driving the taper pins in the reverse direction with an appropriate tool.

The rectangular sections of the knife edge greatly facilitate grinding and sharpening of the knife edge 11, so that it lies parallel to the side faces 23 and the intervening base of the knife edge. This, together with the location of the axis of the opening 15 square with the lever (a simple operation), making it relatively easy to locate knife edges parallel with each other and perpendicular to the lever. It is not serious that the knife edge 11 be displaced from the center plane 24 of the body of the knife edge since appropriate correction may be made by rotating the knife edge as aforesaid and thereafter locking it in position.

In Fig. 1 is illustrated a typical scale lever system equipped with adjustable knife edges. It will be understood, however, that this lever system is only one example of many in which the present invention may be advantageously employed. It is important that the distance from the fulcrum 25 to the pivot 26 be accurately maintained. And similarly that the distance of the pivots 27 and 28 from the fulcrum 29 be constant. Any disturbance in the relation of the various knife edges forming the respective pivots and fulcrums would produce substantial error. The present invention makes it possible 65

not only easily to provide sharp knife edges, but to restore the lever system to its proper ratios, i. e., to "seal" the system with a minimum of labor in the field, and with the assurance that because of the efficient contact between the parts the knife edge will remain in adjusted position. Furthermore, in recording scales or other scales wherein the movement of the scale lever 9 is transmitted by a rack or other connection to recording or indicating mechanism (see Fig. 1), it is very important that parallelism between the respective knife edges be maintained. Otherwise the lever will be twisted or laterally displaced with reference to the connections at 26, 30, and 31. Heretofore in providing sharpened knife edges, it has often been necessary to resort to laborious readjustment of the fulcrum stand 32 and other make-shift adjustments in "sealing" the scale as a result of displacement of the re-sharpened knife edges from their original position. These laborious "sealing" operations are completely dispensed with by the present invention.

The present invention also makes possible substitutions of levers and beams in scale and other lever systems without laborious adjustments to restore the proper lever ratios.

Obviously, the invention is not limited to the details of the illustrative construction since these may be variously modified. Moreover, it is not indispensable that all features of the invention be used conjointly since various features may be used to advantage in different combinations and sub-combinations.

Having described my invention, I claim:

1. An adjustable pivot for a lever or the like comprising in combination a knife edge body, a locking member having a periphery of circular section and an opening therein of a shape to receive and engage the knife edge body, said opening having its longitudinal axis parallel with that at its periphery, means for expanding the said periphery and contracting said opening, a lever having an opening therein of a size and shape to receive said locking member in its unexpanded condition, said locking member being located in the openings in said lever and expanded therein.

2. A locking member for knife edges comprising in combination a body having a periphery of circular section, an opening through said body of a shape to receive a knife edge, said body having resilient portions deflectable to expand said periphery and contract said opening, and means for deflecting said resilient portions.

3. A locking member for knife edges comprising in combination a body having a cylindrical exterior of circular section, an opening through said body of a shape to receive a knife edge, said body being slotted to provide deflectable portions for expanding said exterior and contracting said opening, and wedge means for deflecting said portions.

HARRY M. ROESER.
